UNITED STATES PATENT OFFICE.

WILLIAM L. HARROUN, OF ELLISBURG, NEW YORK, ASSIGNOR TO F. E. HUDSON & SONS, INC., OF ELLISBURG, NEW YORK, A CORPORATION OF NEW YORK.

CLICKER BLOCK.

Application filed July 3, 1928. Serial No. 290,191.

This invention relates to clicker blocks, designed for use in connection with the well-known clicking machines employed in the manufacture of shoes, and has for its object 5 to provide novel construction of an oblong block for cutting leather and the like, the said block comprising a number of segments of hard-wood, or other non-metallic substance, the latter being bound by stout adjustable iron cleats or straps, which are disposed flush with the bottom plane, the portion of the block above the irons being tapered at its four edges for providing a single cutting surface parallel with and of less area 10 than the bottom. A further object is to provide reinforcing rods at intervals in the length of the block, said rods passing entirely through the narrow dimension of the block and through the longer clamping irons 15 which are formed with slotted openings for the purpose, and by which the irons may be clamped tightly against the ends of the segments to prevent buckling or shifting of the irons in case the block shrinks. And a further object is to provide a cutting block of 20 this character having a relatively broad bottom which remains true and level throughout the life of the block and needs no redressing or truing-up, the said bottom not only tending to hold the block level and firm during the cutting operations, but enables a planer to redress its top surface, after the latter becomes worn and uneven, exactly parallel to the bottom. 25 I attain these objects by the means set forth in the detailed description which follows, and as illustrated by the accompanying drawing, in which—

Figure 1 is a top plan view of the sectional block, showing its free top portion tapered, also showing the several clamping and reinforcing members below the taper. Fig. 2 is a side elevation of the block. Fig. 3 is an end elevation of the same. Fig. 4 is a plan view of one of the longer clamping irons. 40 And Fig. 5 is a similar view of one of the shorter irons.

In the drawing, 2 represents the complete clicker block, which is preferably composed 45 of a number of transverse wooden segments 2', that are closely fitted and are usually primarily held together as one part by glue or other adhesive. In practice, the segments 2' are first sawed and jointed and finally assembled without beveling, as shown by dot-

ted lines α in Figs. 2 and 3. These segments may be of uniform or irregular thickness, and when applied to a clicking machine, the block is usually supported by a tray-like base (not shown). 60

Heretofore, clicker blocks of this class were formed with square-cut top and bottom corners and the segments were clamped and held against separation at their joints by iron bars or plates, which were mounted 65 midway in the height of the blocks for providing similar clear portions above, as well as below the irons. The top and bottom faces of these older blocks were parallel, both being finished level and smooth and 70 adapted to be used as cutting surfaces. That is to say, when the uppermost surface of the block becomes worn and uneven, it is turned bottomside upwards and the cutting continued on the new surface. When 75 the original top and bottom faces become worn out by the action of the cutting members, the blocks are sent to the planer and both cutting surfaces are redressed. This wearing away and redressing usually continues until the blocks are reduced to a depth of about one inch greater than the breadth of the clamping irons, after which the remnants of the blocks are discarded and new ones installed. Ordinarily, the redressing 80 stopped about one-half inch clear of the opposite edges of the irons. This results in a considerable waste of the material, as well as loss of the service of the blocks. Furthermore, when the tops and bottoms are both 85 worn out and rendered too uneven for the dies to effect clean cuts, the planer found it difficult to true-up the blocks and restore new cutting surfaces exactly parallel to each other. 90

In the present case, after the segments 2' are assembled and glued together, as described, the top corners at the sides and ends are beveled, as shown in Figs. 1, 2 and 3. The beveling extends upwardly from 100 points adjacent the bottom portions of the sides and ends to the top of the block so as to provide a cutting surface of materially less area than that of the bottom of the block. The unbevelled lower portions of the sides and ends of the block form a continuous ledge or seat 2 α , to engage the clamping irons 3—3'. The clamping or holding irons are disposed substantially flush with the bottom face of the block. These irons are pref- 105 110

erably permanently disposed flush with the extended bottom face of the block, which in practice, is never distorted nor redressed. The breath of the irons 3-3' preferably 5 substantially equals that of the seat 2^a, and their opposite ends extend beyond the corners of the block. One end of each iron is perforated, as at 3^c, and its opposite end is reduced and threaded, as at 3^a. When 10 the irons are mounted on the block 2, the threaded end of one iron is inserted through the perforation 3^c of the adjacent iron, and so on around the block, as shown in Figs. 1, 2 and 3. Nuts 4 are then applied to the 15 ends 3^a, and when tightened up they exert a powerful clamping force both longitudinally and transversely. Owing to the relatively great length of the block 2, the longer irons 3 are liable to spring away from the 20 ends of the segments and render the clamps less effective. To correct this fault, certain of the segments 2' are bored to receive reinforcing rods 5, and the irons 3 are also formed with slotted openings 3^d, through 25 which the threaded ends of the rods protrude sufficiently to receive nuts 5', as shown in Figs. 1 and 2. By disposing the irons 3-3', as shown, the bottom 2^b of the block remains level and unworn, and the top or cutting 30 surface 2^c may be repeatedly redressed until the block is worn down to within about one-half inch of the irons as shown by the dotted line c. This tends to prolong the life of the 35 block, and effects a lowering of the replacement cost, as compared with the older construction, as explained. Naturally blocks of this class are required to be carefully and accurately made from clear stock that is free from knots and hard burls, which might interfere with proper cutting work. The dis-

posing of the irons 3-3' at the bottom instead of midway between the top and bottom as heretofore, the unused bottom surface remains true and level, throughout the life of the block, thereby insuring better and longer 45 service and facilitating the redressing of the blocks and the preserving of the parallel relation of the bottom 2^b and top 2^c, which is indispensable to perfect cutting work.

The bevelling of the block alleviates or lessens chipping or splintering of the corners of the block, due to the fact that the sharp right angular edges of the corners as in the prior art, are eliminated, in which regard it will be noted that the downward pressure 55 of the cutting dies is progressively resisted by the bevelled portions of the block, due to the gradually increasing lower parts of the block. In other words, the vertical lines of force exerted by the cutting dies are opposed 60 by the progressively increasing lower portions of the block, due to such bevelling, whereas with a block having a right angular edge, no such opposition is had and consequently chipping or splintering meets with 65 less resistance.

Having thus described my invention, what I claim is—

A clicker block having its sides and ends bevelled upwardly from points adjacent the bottom portions of said sides and ends to the top of the block so as to provide a cutting surface of less area than that of said bottom of the block, and holding means for the block engaged with said bottom portions of the sides and ends of the block, and disposed substantially flush with the bottom face of the block.

In testimony whereof I affix my signature.

WILLIAM L. HARROUN.
